UNITED STATES PATENT OFFICE.

HENRY M. RUDEN, OF WEST HAVEN, CONNECTICUT.

EXERCISING APPARATUS.

1,344,963.

Specification of Letters Patent. Patented June 29, 1920.

Application filed March 3, 1920. Serial No. 362,995.

To all whom it may concern:

Be it known that I, HENRY M. RUDEN, a citizen of the United States, residing at West Haven, in the county of New Haven and

5 State of Connecticut, have invented a new and useful Improvement in Exercising Apparatus; and I do hereby declare the following, when taken in connection with the accompanying drawings and the characters 10 of reference marked thereon, to be a full, clear, and exact description of the same, and which said drawings constitute part of this application, and represent, in—

Figure 1, a plan view of an exercising 15 apparatus embodying my invention.

Fig. 2, a view thereof in side elevation.

Fig. 3, a detail view of one of the cap-like split bearings, one of which is mounted upon each of the vertically adjustable 20 posts.

Fig. 4, a corresponding view of one of the two adjustable saddles mounted upon the main frame-bar.

Fig. 5, a detached view partly in section 25 and partly in elevation of the abdominal-kneader cam.

Fig. 6, a detached end view of the floor-plate showing its dovetail groove.

Fig. 7, a broken plan view of a separately 30 organized foot-power unit designed to be interchangeably used with the foot-power unit shown in Figs. 1 and 2.

Fig. 8, an end view thereof.

My invention relates to an improved exercising apparatus for use in gymnasiums 35 and in private homes, the object being to produce a compact, easily adjusted apparatus designed to compel the exerciser to make pre-determined, concurrent, circular 40 movements with his arms and legs, and at the same time to assist him in a synchronous movement of the diaphragm whereby the exerciser is led to accompany the movement of his hands and legs with regular, deep 45 breathing.

With these ends in view, my invention consists an an exercising apparatus having certain details of construction and combinations of parts as will be hereinafter de- 50 scribed and pointed out in the claims.

In carrying out my invention, as herein shown, I employ two exercising-wheels 2 and 3 located in the same horizontal plane, each provided on its rim with an up-stand- 55 ing grip or handle 4 and designed to be

spaced apart so that the outer edges of their rims will be separated by about the limit of the reach of the arms of the exerciser when his arms are fully extended.

Centrally behind the exercising-wheels 2 60 and 3, I locate a seat 5 on which the exerciser sits with his feet upon pedals 6 carried by crank-arms 7 on a pedal-shaft 8 mounted in a pedestal 9 dovetailed in a floor-plate 10 in which it is adjustable. 65

Directly in front of the pommel of the seat 5 but above the same, as shown in Fig. 2, I locate an abdominal-kneader 11 centrally arranged between the wheels 2 and 3 as shown in Fig. 1, this kneader being 70 mounted upon the rear end of a reciprocating bar 12 sliding in a bearing 13 pivotally secured to a bracket-arm 14 extending rearwardly from a hub 15 adjustably secured by a clamping-bolt 16 to the main bar 17 of the 75 machine-frame.

To insure the concurrent pre-determined movement of the hands, legs, and abdominal-kneader, the said exercising-wheels 2 and 3, pedals 6 and kneader 11 are geared 80 together so as to act in concert and so that the independent movement of any one of them will effect a corresponding movement of each of the others.

The particular means for connecting and 85 operating the wheels, pedals, and kneader may obviously be varied without departing from my invention.

As herein shown, the exercising-wheels 2 and 3 are rotated against air pressures developed in compression cylinders 18 receiving pistons not shown but carried by piston-rods 19 the outer ends of which swivel upon the pins 20 employed to mount the grips or handles 4 upon the rims of the wheels. The 95 outer ends of the said cylinders 18 are pivotally connected with and supported by the outer ends of swinging arms 21 thereto provided with upstanding studs 22. The inner ends of the said arms 21 are formed with 100 sleeve-bearings 23 by which they are swiveled upon the middle portions of shafts 24 journaled in brackets 25 bolted to the rear faces of saddles 26 mounted upon the main frame-bar 17 and clamped thereupon in any 105 desired position of lateral adjustment by means of clamping-bolts 27, whereby the apparatus is fitted, so to speak, to the arm-reach of a given exerciser.

The exercising-wheels 2 and 3 are fastened 110

to the upper ends of the said shafts 24, the projecting lower ends of which carry bevel-gears 28 meshing into corresponding bevel-gears 29 keyed to the rear ends of horizontal shafts 30 extending transversely under the main frame-bar 17 and provided at their forward ends with corresponding bevel-gears 31 meshing into corresponding bevel-gears 32 on a main shaft 33 arranged in front of and parallel with the main bar 17, but in a plane slightly lower than the same.

The rear ends of the shafts 30 have bearing in the brackets 25 while their forward ends have bearing in brackets 34 secured by bolts 35 to the forward faces of the saddles 26 aforesaid.

Under the construction described, the operation of either or both of the exercising-wheels 2 and 3 effects the rotation of the shaft 33.

For the rotation of the main shaft 33 by leg-power the pedal-shaft 7 is furnished with a bevel-gear 36 corresponding in size and pitch of teeth to all of the bevel-gears thus far mentioned and meshing into a corresponding bevel-gear 37 located within a housing 38 integral with the upper end of the pedal-bracket 9, the shaft 39 of the bevel-gear 37 being connected by a universal joint 40 of any approved construction, with a solid shaft 41 having sliding but not rotary movement in a tubular shaft 42, the forward upper end of which has bearing in a bracket 43 suspended from the main shaft 33.

The projecting forward end of the tubular shaft 42 carries a bevel-gear 44 meshing into a bevel-gear 45 on the main shaft 33, whereby the said shaft 33 becomes a driven shaft in so far as it is operated by leg-power through the pedals 6, or a driving-shaft, in so far as it operates the pedals through power transmitted to it from the wheels 2 and 3 which turn in unison with the pedals irrespective of the source of the motive power.

The abdominal-kneader 11 is reciprocated by means of a uniform motion cam 46 mounted on the shaft 33 and encircled by a cam-ring 47 having a projection 48 in which the forward end of the rod 12 is adjustable. Through its cam 46 the rotary motion of the shaft 33 is converted into the reciprocating motion of the kneader 11, here shown as consisting of a horizontally arranged, transversely bowed or domed plate, but its form and construction may be changed as desired. Thus in place of the bowed plate 11, I might employ an air-cushion or a roller; or the kneader might be dispensed with and replaced by a music-box or mechanical toy to be operated by the cam 46 through the rod 12, for the amusement of a child.

Inasmuch as all of the bevel-gears em-

ployed correspond in size and pitch, it follows that the moving parts of the apparatus will move at the same relative speed under all circumstances, so that however erratic the exerciser may be, the apparatus will never fail to operate synchronously and constantly tend to make him do so.

As shown, the horizontal main frame-bar 17 is mounted at its ends in cap-like split-bearings 48 mounted upon the upper ends of corresponding vertical posts 50 adjustably mounted in flanged sockets 51 adapted to be secured to the floor. As shown, the lower ends of the posts are formed with a series of holes 52 for the reception of pins 53 passing through the upper ends of the sockets. The seat 5 is mounted upon a bracket 54 adjustably mounted upon a seat-post 55 carrying a back-rest 56 vertically adjustable upon the post by means of a hand-wheel 57 and adjustable back and forth with respect to the seat by means of a hand-wheel 58. The said seat-post 55 is formed at its lower end with a dovetail foot 59 adapted to be mounted in the dovetail groove 60 of the floor-plate 10 in which the said post is adjustable back and forth as well as the pedestal 9 of the foot-power unit.

In using my improved apparatus, it is readily adjusted to the reach of the arms and legs of the user by laterally moving the saddles 26 upon the main frame-bar 17, while the height of the main bar 17 above the floor is regulated by adjusting the posts 50 in the sockets 52, this adjustment being taken up by the telescoping action of the solid shaft 41 and tubular shaft 42. It becomes unnecessary to effect a nice alinement of the parts in these adjustments, as any want of perfect alinement is taken up by the universal joint 40. The height of the saddle is easily adjusted by raising or lowering the bracket 54 upon the saddle-post 55. The back-rest 56 is also adjustable up and down and forward and backward as described.

The throw of the abdominal-kneader is not in itself adjustable, but the kneader is adjustable in relation to the seat 4 at the point of the connection of the rod 11 with the ring or strap 47 of the kneader-cam 46, the forward end of the rod 11 having a series of holes 61 receiving a pin 62 passing through the projection 48 of the ring 47.

The cylinders 18 are furnished with valves 63 set to regulate the amount to which the air in the cylinders must be compressed to permit the exercising-wheels 2 and 3 to be turned, thus predetermining the amount of energy that the exerciser must put into the apparatus to operate it at all.

The apparatus having been set as described, the exerciser has no option but to move his hands and feet concurrently and rhythmically, if he would not pit them

against each other; if he does not put forth the effort to operate them rhythmically, the apparatus itself will operate them mechanically. However, the purpose of the 5 apparatus is to lead him to use the proper muscles at the proper time and to expend the proper amount of power to effect rhythmical movement of his arms and legs concurrently with deep rhythmical breathing, in which 10 he is assisted by the abdominal-kneader which compresses the abdomen synchronously with each revolution of the wheels and pedals. If the exerciser allows the 15 diaphragm to descend rhythmically and this is, of course, entirely within his control, a rhythmical movement of the hands and feet and diaphragm, and hence rhythmical breathing, will result.

The foot-power unit described provides 20 for the movement of the feet and legs in the vertical plane after the manner of driving a bicycle. It is made not only adjustable, as described, but is also removable to be interchanged with a foot-power unit 25 constructed for the circular movement of the feet and legs in a horizontal plane, whereby the character of the exercise of the muscles of the feet and legs is somewhat changed. Such a foot-power unit is illustrated in 30 Figs. 7 and 8 of the drawings, in which a bracket-like pedestal 64 is formed with dovetail or beveled edges 65 adapted to be mounted in the dovetail floor-plate 10 shown in Fig. 5, in which it is adjustable back and 35 forth in the same manner as the pedestal 9 of the other foot-power unit. The said pedestal 64 mounts a non-rotatable shaft 66 the projecting ends of which carry brackets 67 in which vertical shafts 68 are journaled, 40 these shafts being provided at their upper ends with crank-arms 69 carrying circular pedal-plates 70 having radially arranged strap-holes 71 providing for the straps by means of which the feet are held in place. 45 The lower ends of the said shafts 68 are furnished with bevel-gears 72 meshing into corresponding gears 73 on a revolving shaft 74 journaled in arms 75 offsetting from the brackets 67. The said shaft 74 mounts a 50 bevel-gear 76 meshing into a bevel-gear 77 mounted in a bracket 78 carried by the shaft 74. The gear-wheel 77 is mounted upon a driving-shaft 79 journaled in the bracket 78 and corresponding to the shaft 39 of the 55 other foot-power unit.

It will be readily understood from the foregoing that the two foot-power units separately organized as they are, may be interchanged according to the requirements 60 of the exerciser.

While I have shown my improved apparatus as driven by gears and shafting, it is obvious that without departing from my invention, I might use sprocket-wheels and 65 sprocket-chains as a means of communicat-

ing motion from the foot-power unit to the main shaft and from the main shaft to the exercising-wheels.

It is also apparent that, if desired, the 70 foot-work may be cut out and the exercising-wheels and abdominal-kneader used alone.

I claim:

1. An exercising apparatus having arm-exercising means rotating in the same horizontal plane, rotary leg-exercising means, 75 operating connections between the said arm- and leg-exercising means whereby they are operated interdependently, and abdomen-exercising means attached to the said connections and operated thereby. 80

2. An exercising apparatus having rotary arm-exercising means, rotary leg-exercising means, means for connecting the said means whereby they are operated interdependently, reciprocatory means for exercising the abdomen, and means for operating the same concurrently with the said arm- and leg-exercising means. 85

3. An exercising apparatus having two exercising wheels located in the same horizontal plane and relatively positioned to be operated by the respective arms of the exerciser, leg-exercising means, a seat and two pedals arranged in proximity to the said wheels, means connecting the said wheels and pedals 90 for their interdependent operation whereby either is operated by the operation of the other, an abdominal-kneader located in front of the said seat and above the same, and means for operating the said kneader concurrently with the exercising of the arms and legs. 95

4. An exercising apparatus having two exercising-wheels located in the same horizontal plane and positioned to be operated by 105 the respective arms of the exerciser, a seat and two pedals, a reciprocating abdominal-kneader located in front of the said seat and above the same, and interdependent driving means for the said wheels, pedals, and 110 kneader.

5. An exercising apparatus having two vertically adjustable posts, a main frame-bar carried thereby, saddles mounted upon the said bar and laterally adjustable thereon, 115 two exercising-wheels respectively supported by the said saddles in position to be operated by the respective arms of the exerciser, a seat, pedals located below the same for operation by the respective legs of the 120 exerciser, a main shaft, a reciprocal abdominal-kneader supported by the said shaft and interdependent connections between the said wheels, pedals, and kneader, whereby the same are operated in unison. 125

6. An exercising apparatus having two exercising-wheels located in the same horizontal plane and positioned for operation by the respective arms of the exerciser, swinging arms mounted co-axially with the said 130

wheels, air-compression means connecting the said wheels and the outer ends of the arms, pedals for operation by the feet of the exerciser, and interdependent connection between the said wheels and pedals.

7. An exercising apparatus having two exercising-wheels located in the same horizontal plane and positioned to be operated by the respective arms of the exerciser, a main frame-bar carrying the said wheels, a seat, a pedal-shaft, and pedals located below the same, a main shaft located to one side of the said main bar, universal adjustable connection between the pedal-shaft and the main shaft, and connection between the wheels and the main shaft including shafts arranged transversely with respect to the main frame-bar, the said connections between the wheels and the pedals being interdependent so that the operation of either or both pedals or either or both wheels effects the corresponding movement of the other corresponding parts.

8. An exercising apparatus having two exercising-wheels located in the same horizontal plane and relatively positioned to be operated by the respective arms of the exerciser, rotary leg-exercising means, connections between the said arm- and leg-exercising means whereby they are operated independently, and a seat positioned with respect to the said arm- and leg-exercising means for the accommodation of the person using them.

In testimony whereof, I have signed this specification in the presence of two subscribing witnesses.

HENRY M. RUDEN.
